UNITED STATES PATENT OFFICE.

ANNIBAL JEAN BAPTISTE LÉGÉ, OF LONDON, ENGLAND.

TURBINE.

No. 915,099.

Specification of Letters Patent. Patented March 16, 1909.

Application filed April 3, 1908. Serial No. 425,004.

To all whom it may concern:

Be it known that I, ANNIBAL JEAN BAPTISTE LÉGÉ, a citizen of the French Republic, of 45 Lofting road, Barnsbury, London, England, engineer, have invented a certain new and useful Improvement in Turbines, of which the following is a full, clear, and exact description, and for which I have applied for Letters Patent in Great Britain, No. 7,955, 10 dated April 5, 1907.

This invention relates to certain improvements in turbines, whether the acting fluid be of an expanding nature or of a non-expanding one, and it has for its purpose to 15 utilize to the best advantage the energy contained in the fluid used, and to avoid back pressure.

The invention has reference to the type of turbine in which the fluid exerts a pressure 20 upon moving piston-vanes attached to the rotor, this pressure being maintained in the forward direction by the incoming tangential jet of fluid. This jet is of the full width of the chamber into which it plays and while 25 maintaining the forward pressure, it prevents any escape of fluid in the reverse direction; the portion of the chamber to the rear of the jet is in fact open to exhaust by a port situated behind the inlet port. Each piston- 30 vane is thus exposed upon one face to the pressure maintained by the jet of fluid and upon the other face to the pressure of the exhaust. The driving effort is obtained by 35 the difference between these pressures as in a reciprocating engine; this distinguishes the present type of turbine from impact, impulse and reaction turbines.

The present invention consists in certain improvements in turbines of this type, for 40 the purposes of reducing the back-pressure upon the piston-vanes and of rendering the turbine more suitable for use as a compound or as a multi-stage machine.

This turbine consists of two principal parts, 45 the stationary part which contains the means of admission of the fluid (which said means may be in the shape of expanding nozzles or of slots with a view to cause an increase of velocity of the fluid), the means of exhaust 50 and annular recesses to form chambers; and the other part is the rotor or rotating part or disk carrying the one or more piston-vanes, or pressure receiving arrangements, and this disk is fixed on the shaft.

55 The invention utilizes a fluid jet coming

from for example a nozzle, this jet playing more or less tangentially or obliquely to the direction of rotation into a chamber. This chamber is formed by an annular recess in the stationary part, and one side of the rotating part. The aforesaid jet plays against and provides the fluid which presses against a piston-vane or pressure-receiving arrangement. This pressure receiving arrangement forms part of the rotating portion and is free 60 to move in the above-named annular recess, and the velocity of said jet of fluid which is of the whole width of the chamber into which it plays, causes it to form a kind of wall which separates the fluid in front of it from 65 any fluid at the back of it, so that all the energy of the incoming jet acts in advance of said jet. The invention also comprises, in combination with the foregoing arrangement to afford a steam or gas wall, a means 70 of exhaust placed at any point close to the back part of the said jet in such a way as not to disturb the jet's full action and placed at any one of the sides of the stationary part of the chamber into which the jet plays, excepting the nozzle side that is the side the jet 75 comes from. The reason for this arrangement of the exhaust is to allow by its direction the outgoing fluid to retain and continue its own line of motion (instead of being bent 80 back on itself) which thus remains practically the same as the direction of its working in the chamber, and also in the case of gradual expansion of fluid, as where the engine is compound, this direction of exhaust enables 85 the exhausting arrangement of one chamber to form or become the means of inlet into the next larger chamber.

Upon the accompanying drawings I have 90 illustrated my invention as applied to multi-stage steam turbines.

Figure 1 is an end elevation of a turbine, the upper part being in central section. Fig. 2 is a sectional elevation at right angles to Fig. 1. Fig. 3 is a sectional elevation of a modified turbine in which the fluid passes through annular chambers arranged in axial succession. Figs. 4 and 5 are explanatory diagrams.

In Figs. 1 and 2, the turbine casing *a* is 105 formed with a jacket *b* to which the steam is admitted. The nozzles *c* receive steam from this jacket and deliver it in a tangential direction against the first series of piston vanes *d* rotating in the first annular chamber *e*. 110

The internal wall of this chamber *e* consists of a ring *f* integral with the casing *a* and having a number of passages *g* therethrough. These passages *g* form a means of exhaust for the chamber *e* and also a means of delivery for a second chamber *h*, into which the steam is directed tangentially to the piston-vanes *i* rotating therein. The position of the passages *g* in the ring *f* is such that the piston uncovers the passage for exhaust just before it reaches the incoming jet from the nozzle *c*, while the passage lies behind the line of the nozzle so that the area of high pressure in front of the nozzle is always separated from the area of low pressure at the exhaust passage by the dividing wall constituted by the incoming steam. In a similar manner the second chamber *h* exhausts through passages *j* in another ring *k* to a third annular chamber *l*, the steam being directed again tangentially against the pistons *m*. From this chamber the steam exhausts through ports *n* to a conduit *o* leading to the condenser. A fourth annular chamber *p* is shown for the purposes of reversing, and to effect this, steam is introduced to a central chamber *q* and delivered through nozzles *r* against piston-vanes *s*. For the sake of clearness I have shown separate exhaust-ports *n*¹ for the reversing chamber. The exhaust from this chamber may however be led through passages in the ring *t*, similar to the passages *g*, *j*, and directed against the pistons *m* and so to the exhaust at *n* as before, or the reversing steam may be carried one or more stages further into the chambers *h*, *e*, and thence exhausted, the communicating passages being suitably formed for this purpose. The piston-vanes *d*, *i*, *m* are mounted upon a disk *u*, secured to a shaft *v*, and a similar series of chambers and pistons is arranged upon the other side of the disk, one series only being shown in section in Fig. 2. The steam pressure upon the one side of the disk is thus caused to balance that upon the other side, so that no end-thrust results. Where, as in a turbine for driving a screw propeller, end-thrust is advantageous, only one series of pistons and chambers may be employed. It will be understood that the number of annular chambers will be determined by the requirements of each individual case. Between the disk and the stationary parts, a steam packing is introduced consisting of concentric grooves and fillets to prevent leakage.

In Fig. 3 is shown a modified construction in which the annular chambers are no longer placed concentrically one with another, but in different planes in axial succession along the shaft. In a turbine of this type, as in the case of the reversing nozzles *r* of the previously-described turbine, the nozzles cannot conveniently be arranged to deliver tangentially into the chambers.

They are therefore placed as shown at a slight inclination which is kept as small as circumstances will allow. The steam is admitted to a steam-chest *b*¹ within which the nozzles *c* are located, and passes successively as before through chambers *e*, *h*, *l* and a fourth chamber *p*¹ to the exhaust conduit *o* leading to the condenser. Each of the intermediate rings *f*, *k*, *t* is formed with packing grooves and fillets corresponding with fillets and grooves upon the rotor *u*; similar packing is provided at each extremity of the rotor. The exhaust-inlet passages in this turbine are formed in a similar manner to those in the previous construction; the machine may therefore be reversed by passing steam in a contrary direction, for instance by admitting it to the exhaust conduit and exhausting at one of the early stages, say chamber *h*. The quantity of steam passing will depend upon the size of the chamber from which the exhaust takes place; to obtain additional power in reversing it may therefore be necessary to release a portion of the steam at an intermediate stage. Similarly, to obtain additional torque at starting or other times, additional steam of high pressure may be admitted direct to all or any of the stages. Suitable slide or other valves for these purposes are arranged in the turbine as required.

Fig. 4 shows in section a form of blade, which may be employed in this type of turbine to obviate end-thrust. In this blade, the two internal faces of the blade are so designed that their geometrical projections parallel to the shaft are equal; the two longitudinal components of the pressures (acting upon the blades as shown by the arrows) will therefore neutralize one another and the resultant pressure will be purely tangential. As previously stated, however, with reference to the former type, it may be advantageous in certain cases to allow of end-thrust upon the rotor; in such cases one or other of the internal faces of the blade will be reduced according to the end-thrust required.

Fig. 5 shows diagrammatically in its simplest form the principle of the present invention. The chamber *e* receives steam for one of its sections at A in the direction shown, this being approximately tangential to the path of the piston. The exhaust takes place from the preceding section either to condenser or to a second stage in either direction B, direction C, or direction D. In any case the exhaust passage is not immediately opposite to the jet A but is some distance behind (against the direction of the piston) so that a wall of steam is formed to separate the high pressure area in front of the jet from the low pressure area at the exhaust passage.

The piston-vanes or pressure-receiving

- devices may be provided with holes or apertures passing through them and forming nozzles so as to favor velocity of the fluid and either create a vacuum at the front of 5 the piston-blade or pressure-receiving arrangement, or to counter fluid pressure against it, and also as a means to favor a slower speed of the engine without loss of power.
- 10 I am aware that in rotary engines having a radial flow, two similar units have been arranged symmetrically upon the shaft for the purpose of balancing end-tarust and to such arrangement I make no claim, but
- 15 Having thus described my invention, what I claim as such and desire to secure by Letters Patent is:—
1. A turbine comprising a stator, a chamber in said stator, walls to said chamber, a 20 rotor, widely separated piston vanes upon said motor, said vanes traveling in said chamber, an inlet nozzle arranged to discharge through one wall of said chamber, and an exhaust passage in a second wall of the 25 chamber and arranged immediately to the rear of the inlet nozzle whereby the fluid admitted through said nozzle forms a separating wall which prevents the passage to exhaust of fluid from said chamber in advance 30 of said nozzle in relation to the direction of rotation.
2. A turbine, comprising a stator, a chamber in said stator, walls to said chamber, a rotor, widely separated piston-vanes upon 35 said rotor, said piston-vanes traveling in said chamber, a nozzle in a wall of said chamber adapted to deliver fluid into the chamber, and an exhaust passage in a second wall of said chamber in rear of the nozzle whereby 40 the fluid entering the chamber forms a separating wall which divides the chamber into a forward portion of high pressure and a rearward portion which is open to the exhaust passage.
- 45 3. A turbine, comprising a stator, a chamber in said stator, walls to said chamber, a rotor, piston vanes upon said rotor, said piston-vanes being widely separated and traveling in said chamber, a nozzle in a wall of said 50 chamber adapted to admit fluid into the chamber, and an exhaust passage in a second wall of said chamber, said exhaust lying immediately to rear of said nozzle, said nozzle adapted to admit a jet which is substantially 55 the full width of the chamber whereby the fluid forms a separating wall which prevents the passage to exhaust of fluid from said chamber in advance of said nozzle in relation to the direction of rotation.
- 60 4. A turbine, comprising a stator, a chamber therein, walls to said chamber, a rotor, piston-vanes upon said rotor, said piston-vanes being widely separated and traveling in said chamber, a plurality of nozzles in a 65 wall of said chamber each adapted to deliver

fluid into the chamber between a pair of vanes, and exhaust passages in a second wall of said chamber, each of said exhaust passages being located immediately to rear of an inlet nozzle whereby the admitted fluid forms 70 a separating wall which divides the chamber into a forward portion of high pressure and a rearward portion which is open to the exhaust passage.

5. A turbine, comprising a stator, chambers in said stator, walls to said chambers, a rotor, piston-vanes upon said rotor, said piston-vanes being widely separated and traveling in said chamber, nozzles in a wall of said chambers and adapted to deliver fluid thereinto between separated vanes, and exhaust passages in a second wall of said chambers, each of said passages being arranged immediately to the rear of an inlet nozzle whereby the fluid admitted through said nozzle forms 80 a separating wall which prevents the passage to exhaust of fluid from the chamber in advance of said nozzle in relation to the direction of rotation.

6. A turbine, comprising a stator, chambers in said stator, walls to said chambers, a rotor, piston-vanes upon said rotor, said piston-vanes being widely separated and traveling in said chambers, nozzles in a wall of one of said chambers adapted to deliver fluid into 90 the chamber, passages in a second wall of said chamber, said passages leading to a wall of a second of said chambers, and exhaust passages in a second wall of said second chamber and arranged immediately to the 95 rear of the inlet nozzle of that chamber whereby the fluid forms a separating wall which divides the chamber into a forward portion of high pressure and a rearward portion which is open to the exhaust passage of 100 the chamber.

7. A turbine, comprising a stator, chambers in said stator, walls to said chambers, a rotor, piston-vanes upon said rotor, said piston-vanes being widely separated and traveling in said chambers, nozzles in a wall of one of said chambers adapted to deliver fluid thereinto, passages in a second wall of said first chamber, said passages lying immediately to rear of said nozzles whereby the fluid 110 admitted to the chamber forms a separating wall which prevents the passage to exhaust of fluid from said chamber in advance of the nozzle of that chamber in relation to the direction of rotation, said second wall of said 115 first chamber constituting a wall of said second of said chambers, and exhaust passages in a second wall of said second chamber, said exhaust passages lying immediately to rear of said passages whereby the fluid admitted 120 to said second chamber forms a separating wall which divides the chamber into a forward portion of high pressure and a rearward portion which is opened to the exhaust portion of said second chamber.

8. A turbine, comprising a stator, chambers in said stator, walls to said chambers, a rotor, piston-vanes upon said rotor, said piston-vanes traveling in said chambers, nozzles in a wall of one of said chambers, fluid delivered through said nozzles, passages in a second wall of said first chamber, said passages lying immediately to rear of said nozzles and leading through a wall of a second of said chambers, second passages in a second wall of said second chamber, said second passages leading through a wall of a third of said chambers, and exhaust passages in a second wall of said third chamber, said exhaust passages lying immediately to rear of said second passages.

9. A turbine, comprising a stator, chambers in said stator, walls to said chambers, a rotor, piston-vanes upon said rotor, said piston-vanes being widely separated and traveling in said chambers, nozzles in a wall of one of said chambers adapted to deliver fluid thereinto, passages in a second wall of said chambers, said second wall of said first chamber constituting a wall of said second of said chambers, second passages in a second wall of said second chamber, said second wall of said second chamber constituting a wall of said third of said chambers, and exhaust passages in a second wall of said third chamber and arranged immediately to the rear of the inlet thereto, whereby the fluid admitted to the chamber forms a separating wall which prevents the passage to exhaust from said chamber in advance of said nozzle in relation to the direction of rotation.

10. A turbine, comprising a stator, chambers in said stator, walls to said chambers, a rotor, piston-vanes upon said rotor, said piston-vanes traveling in said chambers, nozzles in a wall of one of said chambers, fluid delivered through said nozzles, passages in a second wall of said first chamber, said passages lying immediately to rear of said nozzles, said second wall of said first chamber constituting a wall of a second of said chambers, second passages in a second wall of said second chamber, said second passages lying immediately to rear of said passages, said second wall of said second chamber constituting a wall of a third of said chambers, and exhaust passages in a second wall of said third chamber, said exhaust passages lying immediately to rear of said second passages.

11. A turbine, comprising a stator, chambers in said stator, walls to said chambers, a rotor, piston-vanes upon said rotor, said piston-vanes being widely separated and traveling in said chambers, nozzles in a wall of one of said chambers, passages for the exit of fluid from said chambers said passages being arranged immediately to rear of a corresponding inlet nozzle, reversing nozzles in a wall of the last of said chambers and arranged immediately in rear of said exit pas-

sages whereby the fluid is delivered by the reversing nozzles in a direction opposite to said nozzles in said first chamber.

12. A turbine, comprising a stator, chambers in said stator, walls to said chambers, a rotor, piston-vanes upon said rotor, said piston-vanes being widely separated and traveling in said chambers, nozzles in a wall of one of said chambers, passages in a second wall of said first chamber and leading through a wall of a second of said chambers, second passages in a wall of said second chamber and leading through a wall of a third of said chambers, exhaust passages in a second wall of the third chamber, and reversing nozzles in a wall of a fourth of said chambers and arranged immediately in rear of the exhaust passages of that chamber.

13. A turbine, comprising a stator, chambers in said stator, walls to said chambers, a rotor, piston-vanes, upon said rotor, said piston-vanes traveling in said chambers, nozzles in a wall of one of said chambers, passages in a second wall of said first chamber, said passages lying immediately to rear of said nozzles and leading through a wall of a second of said chambers, second passages in a second wall of said second chamber, said second passages lying immediately to rear of said passages and leading through a wall of a third of said chambers, exhaust passages in a second wall of said third chamber, said exhaust passages lying immediately to rear of said second passages, reversing nozzles in a wall of a fourth of said chambers, fluid delivered by said reversing nozzles and exhaust passages in a second wall of said fourth chamber, said exhaust passages lying immediately in front of said reversing nozzles.

14. A turbine, comprising a stator, chambers in said stator, walls to said chambers, a rotor, piston-vanes upon said rotor, said piston-vanes traveling in said chambers, nozzles in a wall of one of said chambers, passages in a second wall of said first chamber, said passages leading through a wall of a second of said chambers, second passages in a second wall of said second chamber, said second passages leading through a wall of a third of said chambers, exhaust passages in a second wall of said third chamber, reversing nozzles in a wall of the fourth of said chambers, fluid delivered by said reversing nozzles, and passages in a second wall of said fourth chamber, said second wall of said fourth chamber constituting a third wall of said third chamber.

15. A turbine, comprising a stator, concentric chambers in said stator, walls to said chambers, a rotor, piston-vanes upon said rotor, said piston-vanes being widely separated and traveling in said chambers, nozzles in the outer wall of the outermost of said chambers, fluid delivered through said nozzles, passages in the wall between said outermost and the second of said chambers,

second passages in the wall between said second and the third of said chambers, and exhaust passages in a second wall of said third chamber, said fluid forming a separating wall dividing said chamber into a forward portion of high pressure and a rearward portion open to said exhaust passage.

16. A turbine, comprising a stator, concentric chambers in said stator, walls to said chambers, a rotor, piston-vanes upon said rotor, said piston-vanes traveling in said chambers, nozzles in the outer wall of the outermost of said chambers, fluid delivered through said nozzles, passages in the wall between said outermost and the second of said chambers, said passages lying immediately to rear of said nozzles, second passages in the wall between said second and the third of said chambers, said second passages lying immediately to rear of said passages, and exhaust passages in a second wall of said third chamber, said exhaust passages lying immediately to rear of said second passages.

17. A turbine, comprising a stator, concentric chambers in said stator, walls to said chambers, a rotor, piston-vanes upon said rotor, said piston-vanes traveling in said chambers, nozzles in the outer wall of the outermost of said chambers, passages in the wall between said outermost and the second of said chambers, said passages lying immediately to rear of said nozzles, second passages in the wall between said second and the third of said chambers, said second passages lying immediately to rear of said passages, exhaust passages in a second wall of said third chamber, said exhaust passages lying immediately to rear of said second passages, reversing nozzles in the inner wall of the innermost of said chambers, fluid delivered by said reversing nozzles, and exhaust passages in a second wall of said innermost chamber lying immediately in front of said reversing nozzles.

45 18. A turbine, comprising a stator, concentric chambers in said stator, said chambers being in two symmetrical series, walls to said chambers, a rotor, piston-vanes arranged symmetrically upon either side of said rotor, said piston-vanes traveling in said chambers, nozzles in the outer wall of each outermost chamber, passages in the wall between the outermost and the second of each series of chambers, second passages in the wall between the second and the third of each series of chambers, exhaust passages

in a second wall of said third chamber of each series, reversing nozzles in the inner wall of each innermost chamber, fluid delivered by said reversing nozzles, and exhaust passages in a second wall of each said innermost chamber.

19. A turbine, comprising a stator, concentric chambers in said stator, said chambers being in two symmetrical series, walls to said chambers, a rotor, piston-vanes arranged symmetrically upon either side of said rotor, said piston-vanes traveling in said chambers, nozzles in the outer wall of each outermost chamber, fluid delivered through said nozzles, passages in the wall between the outermost and the second of each series of chambers, said passages lying immediately to rear of said nozzles, second passages in the wall between the second and the third of each series of chambers, said second passages lying immediately to rear of said passages, and exhaust passages in a second wall of the third chamber in each series, said exhaust passages lying immediately to rear of said second passages.

20. A turbine, comprising a stator, concentric chambers in said stator, said chambers being in two symmetrical series, walls to said chambers, a rotor, piston-vanes arranged symmetrically upon either side of said rotor, said piston-vanes traveling in said chambers, nozzles in the outer wall of each outermost chamber, passages in the wall between the outermost and the second of each series of chambers, said passages lying immediately to rear of said nozzles, second passages in the wall between the second and the third of each series of chambers, said second passages lying immediately to rear of said passages, exhaust passages in a second wall of said third chamber of each series, said exhaust passages lying immediately to rear of said second passages, reversing nozzles in the inner wall of each innermost chamber, fluid delivered by said reversing nozzles, and exhaust passages in a second wall of each said innermost chamber lying immediately to rear of said reversing nozzles.

In witness whereof, I have hereunto set my hand in presence of two witnesses.

ANNIBAL JEAN BAPTISTE LÉGÉ.
